UNITED STATES PATENT OFFICE.

WILLIAM H. PALMER AND WILLIAM H. DANIEL, OF CHICAGO, ILLINOIS.

STALLION-SHIELD.

SPECIFICATION forming part of Letters Patent No. 471,567, dated March 29, 1892.

Application filed January 4, 1892. Serial No. 417,038. (No model.)

To all whom it may concern:

Be it known that we, WILLIAM H. PALMER and WILLIAM H. DANIEL, citizens of the United States, residing at Chicago, in the county of 5 Cook and State of Illinois, have invented new and useful Improvements in Guards or Shields for Stallions, of which the following is a full description, reference being had to the accompanying drawings, in which—

10 Figure 1 shows the device applied to a stallion. Fig. 2 is a longitudinal vertical section of the guard or shield, the attaching-straps being broken away. Fig. 3 is a perspective view of the guard or shield, the attaching- 15 straps being broken away; and Fig. 4 is a detail, being a top or plan view of the back-pad to which the shield-supporting straps are attached.

Our invention relates to a device for use with 20 stallions for the prevention of masturbation, as hereinafter more fully described. That which we claim as new will be pointed out in the claims.

In the drawings, A represents the guard or 25 shield, which may be made of india-rubber or of other suitable material. We prefer to use india-rubber, as this material is easily molded into the desired shape, is impervious to fluids, and is more readily cleansed. The guard or 30 shield A is approximately triangular in shape, and the edges a are turned up on each side to give it somewhat of a dish shape.

The guard or shield A is formed with its forward end A' turned up at right angles, or 35 nearly so, with the body of the guard, so as to form a front wall, against which the penis of the animal will come if thrust out inside of the guard or shield. We prefer to form the guard or shield of one piece molded in 40 the shape described and shown.

B is an opening in the guard or shield A. The opening B is shown as substantially ovoid in form, with the narrow end in front.

C is a metal plate having an opening of the 45 same size and shape as the opening B in the shield A. The metal plate C is attached to the shield A in any suitable manner in such a way that the opening B in the shield A and that in the plate C will coincide. The 50 opening in the plate C is provided at its forward end with inwardly-projecting points or teeth b upon each side.

The shield or guard A is provided with points c upon its upper and inner surface, located upon each side of the opening B and 55 toward the forward portion of the shield. The upwardly-projecting portion A' is provided with points c', projecting backward from its rear or inner surface. The points c c' may be molded around metallic pins, as is best 60 shown in Fig. 2, when the shield or guard is formed of india-rubber or they may be formed in any suitable manner.

D indicates a strap secured in any suitable manner to the rear end of the guard or 65 shield A. The strap D may be bifurcated to form a tail-piece D', or the tail-piece may be formed of independent straps secured to the strap D. The strap D and tail-piece D' may be made of india-rubber, leather, or any other 70 suitable material.

E indicate straps secured in any suitable manner to each forward corner of the shield or guard A.

F is a strap secured in any suitable man- 75 ner to the front portion A' of the guard or shield A, at or near the middle of the front portion A'. The strap F is long enough to pass forward between the fore legs of the animal and upward to connect with a collar G. 80 The collar G is made of leather or other suitable material and is of such size and shape as to fit around the base of the neck of the animal.

H indicates a pad made of leather or other 85 suitable material, which pad may be perforated with openings h to permit ventilation.

III indicate snap-hooks—four in number— secured in any suitable manner to the pad H, one upon each side of said pad. K indicates 90 a strap to connect the tail-piece D' with the pad H, and L indicates a strap to connect the pad H with the collar G. The straps E, F, K, and L may be provided with buckles s or other suitable devices for the purpose of adjusting the length of the straps E, F, K, and L to the size of the horse. The straps E, K, and L are provided with rings M M at their free ends, adapted to engage with the snap-hooks I upon the pad H. The collar G is provided with a snap-hook g and ring g' or with other suitable devices adapted to secure the collar G about the neck of the animal. 100

It will readily be seen that by means of the

snap-hooks I and the rings M and the snap-hook *g* and ring *g'* the shield or guard can be easily and quickly put on or removed from the animal.

5 In use the shield or guard is attached to the animal as is shown in Fig. 1. The opening B in the guard or shield A is of such size and comes in such a position when the guard or shield is put upon the animal that the penis of the stallion may be extended downward through the opening in urinating. If, however, the member is further protruded and thrown up, it will come in contact with the teeth or points *b* of the plate C and will be 15 instantly withdrawn, thus preventing masturbation. In case the animal extends the member forward or to either side within the shield it will come in contact with the points *c* or *c'*, causing the immediate withdrawal of 20 the member and preventing masturbation.

The shield or guard above described is simple and effective, is easily and quickly removed or put on, is readily cleansed, and, inasmuch as the shield is provided with an opening through which the animal's penis may 25 pass when the animal desires to urinate, the

shield does not become foul, the urine being discharged outside instead of inside of the shield.

What we claim as new, and desire to secure 30 by Letters Patent, is—

1. The shield or guard A, having its forward end A' turned up and provided with the points *c c'* and having an opening B for the passage of the penis, substantially as de- 35 scribed.

2. The combination, with a shield or guard A, provided with points *c c'* upon its upper surface and having the opening B for the passage of the penis, of a plate C, provided with 40 a similar-shaped opening, substantially as described.

3. A stallion-shield having an upturned end A' and an ovoid-shaped penis-opening having laterally-projecting pins *b* on the edges of its 45 narrowing portion, substantially as described.

WILLIAM H. PALMER.
WILLIAM H. DANIEL.
